US00D664704S

(12) **United States Design Patent**
Boyer et al.

(10) **Patent No.:** US D664,704 S
(45) **Date of Patent:** ** Jul. 31, 2012

(54) **LIGHTING FIXTURE**

(75) Inventors: **John D. Boyer**, Lebanon, OH (US);
James G. Vanden Eynden, Indian
Springs, OH (US); **Larry Akers**,
Clarksville, OH (US)

(73) Assignee: **LSI Industries, Inc.**, Cincinnati, OH
(US)

(**) Term: **14 Years**

(21) Appl. No.: **29/405,425**

(22) Filed: **Nov. 2, 2011**

Related U.S. Application Data

(63) Continuation of application No. 13/286,400, filed on
Nov. 1, 2011.
(51) **LOC (9) Cl.** **26-03**
(52) **U.S. Cl.** **D26/92**
(58) **Field of Classification Search** D26/92,
D26/67-71; 362/249.01-249.06, 294, 373,
362/431

See application file for complete search history.

(57) **CLAIM**

The ornamental design for lighting fixture, as shown and
described.

DESCRIPTION

FIG. 1 is a perspective view of a first embodiment of the
design of the present disclosure;

FIG. 2 is a front side view of the embodiment depicted in FIG.
1;

FIG. 3 is a rear side view of the embodiment depicted in FIG.
1;

FIG. 4 is a left side view of the embodiment depicted in FIG.
1;

FIG. 5 is a right side view of the embodiment depicted in FIG.
1;

FIG. 6 is a top view of the embodiment depicted in FIG. 1;
and,

FIG. 7 is a bottom view of the embodiment depicted in FIG.
1.

Those portions of the present invention which are presented
in phantom illustrate the environment of the design only and
form no part of the claimed design. Moreover, the shading
presented in the accompanying drawings is provided merely
to highlight the contour of the invention and is not intended to
be illustrative of texture or gloss.

1 Claim, 5 Drawing Sheets
